UNITED STATES PATENT OFFICE.

ALLIE R. WELCH AND FRED STIMSON WELCH, OF PONTIAC, MICHIGAN.

AUTOMOBILE-FRAME.

No. 809,656.

Specification of Letters Patent.

Patented Jan. 9, 1906.

Application filed May 29, 1905. Serial No. 262,782.

To all whom it may concern:

Be it known that we, ALLIE RAY WELCH and FRED STIMSON WELCH, citizens of the United States, residing at Pontiac, county of 5 Oakland, State of Michigan, have invented a certain new and useful Improvement in Automobile-Frames; and we declare the following to be a full, clear, and exact description of the invention, such as will enable others 10 skilled in the art to which it pertains to make and use the same, reference being had to the accompanying drawings, which form a part of this specification.

This invention relates to automobile-frames; and the object of our improvements 15 is to secure an improved frame having increased strength at the part where it is narrowed down toward the front of the machine.

In the drawings, Figure 1 is a perspective 20 view of the frame embodying our invention. Fig. 2 is a section on the line 2 2 of Fig. 1.

A A are the side pieces, bent inward at A² 25 and continued in the direction of the parts A A in A' A'. The side pieces are preferably 25 U-shaped in cross-section, the hollow being inward.

B B are metal strips, each lying toward one 30 end in the hollow of the portion A' of the side pieces for a considerable part of the length of 30 said portion and extending toward the other end parallel to the portions A A of the side pieces.

C is a cross-piece extending across the 35 frame and riveted to the portions A A of the frame and having the ends of the metal pieces B secured thereto by rivets.

B' is a cross-piece extending from one of the pieces B to the other and riveted at its ends to said metal pieces.

40 D is the crank-case of the engine, secured to the bent-in portions A' A' of the frame by studs d and forming a brace to this portion of the frame.

In frames of the kind herein illustrated it 45 has been found that they are liable to give way or bend at the portions A² A², where the broader portion is bent inward and continued in the narrow portion. The construction above described strengthens the frame at 50 these parts and forms a girder-like construction which not only prevents strain from vertical forces, but is adapted to resist horizontal stresses.

The strips B are made of a size and shape

that shall bring their edges against the flanges 55 of the portion A' of the side pieces.

What we claim is—

1. In a vehicle-frame, the combination of a side piece bent inward for a portion of its length and a strip rigidly secured to the bent-in portion of said side piece, extending beyond said bent-in portion at a distance from said side piece and rigidly secured toward its end to said side piece.

2. In a vehicle-frame, the combination of two side pieces bent inward for adjacent portions of their lengths, a strip rigidly secured to the bent-in portion of each of said side pieces extending beyond said bent-in portion at a distance from said pieces and means for 70 rigidly securing said strips together and to the side pieces at points remote from said bent-in portions of the side pieces.

3. In a vehicle-frame, the combination of two side pieces bent inward for adjacent portions of their lengths, a strip rigidly secured to the bent-in portion of each of said side pieces extending beyond said bent-in portion at a distance from said pieces and means for rigidly securing said strips together and to 75 the side pieces at points remote from said bent-in portions of the side pieces, and a brace extending between said bent-in portions of the side pieces.

4. In a vehicle-frame, the combination of two side pieces bent inward for adjacent portions of their lengths, a strip rigidly secured to the bent-in portion of each of said side pieces extending beyond said bent-in portion at a distance from said pieces and means for 90 securing said strips rigidly together and to the side pieces at points remote from said bent-in portions of the side pieces, and a brace extending between said strips.

5. In a vehicle-frame, the combination of two side pieces bent inward for adjacent portions of their lengths, a strip secured to the bent-in portion of each of said side pieces, extending beyond said bent-in portion at a distance from said pieces, means for securing 100 said strips rigidly together and to the side pieces at points remote from said bent-in portions of the side pieces, and a crank-case secured to said bent-in portions of the side frames, and serving as a brace therefor.

105 6. In a vehicle-frame, the combination of a side piece U-shaped in cross-section bent inward for a portion of its length and a strip

rigidly secured to the bent-in portion of said side piece within the hollow of the U-shaped cross-section with its edges abutting against the flanges, said strip extending beyond said 5 bent-in portion at a distance from said side piece and rigidly secured toward its end to said side piece.

In testimony whereof we sign this specification in the presence of two witnesses

ALLIE R. WELCH.

FRED STIMSON WELCH.
